UNITED STATES PATENT OFFICE

2,514,009

BUBBLE-FORMING DEVICE.

August Raspel, Locust Valley, N. Y., assignor to
Aviation Research and Development Corpora-
tion, Waco, Tex., a corporation of Delaware

Application October 15, 1945, Serial No. 622,308

2 Claims. (Cl. 46—6)

1

This invention relates in general to a device for forming bubbles and in particular to bubble-forming devices commonly referred to as wands, and includes correlated improvements designed to enhance the utility and increase the efficiency of such devices.

In my prior application Ser. No. 560,519, filed October 26, 1944, now U. S. Patent 2,433,625; issued December 30, 1947, I have disclosed a composition for forming air borne freely floating bubbles of large size for use in aeronautic investigations of air currents, for display, advertising and entertainment. When forming bubbles of such a composition, it is customary to dip into a liquid a wand comprising an elongated handle terminating in a circular member or ring. Heretofore, such wands have been made of a single piece of wire having a circular cross-section, the diameter of the wire being approximately $1/32$ of an inch. When such a wand is dipped into the bubble-forming composition, a film is formed over the ring and when the wand is drawn through the air, a multiplicity of bubbles are produced. It has been found that the number of bubbles which are produced are a function of the amount of liquid held on the ring. It is desirable therefore to increase the total volume of the liquid in order to increase the number of bubbles. When an attempt is made to accomplish this object by increasing the diameter of the wire, there is no substantial increase in the number of bubbles produced. As a matter of fact, when the diameter of the wire reaches one-quarter of an inch, there is actually a gradual decrease in the number of bubbles produced, the viscosity of the liquid and all other factors being kept constant. On the other hand, there is no substantial increase in bubbles as a result of diminishing the diameter of the wire.

Accordingly, it is a general object of the present invention to provide a wand of the ring type which will have greater bubble-forming characteristics than wands heretofore known.

Another object of the invention is to provide means for simultaneously strengthening a bubble-forming wand and increasing its bubble-forming characteristics.

Other objects of the invention will in part be obvious and will in part appear hereinafter.

According to the present invention there is provided a wand having a handle and a bubble-forming ring thereon, said ring comprising, in cross-section, a multiplicity of strands of rigid material, said strands being so associated that capillary spaces are provided between them.

2

For a more complete understanding of the nature and objects of the invention, reference should be had to the accompanying drawing in which:

5 Figure 1 is a perspective view of one embodiment of the wand of the present invention;

Figure 2 is a cross-section of the ring of the wand illustrated in Fig. 1, taken along the line 2—2 thereof and showing the ring carrying bubble-forming liquid;

Figure 3 is a perspective view of a second embodiment of the present wand;

Figure 4 is a cross-section of the bubble-forming ring of Fig. 3;

15 Figure 5 is a third embodiment of the wand;

Figure 6 is another embodiment of the wand;

It has now been found that by forming at least the ring section of the wand of a plurality of small diameter elements and providing small 20 capillary spaces between said elements, a very greatly increased surface area is provided. Accordingly, the area of contact of the bubble-forming liquid with the ring elements is much greater than when a single wire or ring element 25 is employed. In addition, liquid is held in the capillary spaces between the elements.

Referring to Fig. 1 in its simplest embodiment, the wand is formed of at least two wires 10 and 10' which, for convenience, may be associated together by twisting and forming into a ring 11.

If desired, the handle portion 12 of the wand may also be formed of the twisted elements if increased rigidity of the handle is desired. On the other hand, the twisted elements may be confined to the ring portion as illustrated, for example, in Figure 3. When the wand shown in Fig. 1 is dipped in the bubble-forming liquid, the wire elements 10 and 10' are surrounded by a large spherical coating of liquid 13, as shown in Fig. 2. The total volume of the liquid held on the multiple expanded ring is greater than would be held upon a single strand of the diameter of the strand 10 or upon a single strand having a surface area equal to the sum of the surface areas 10 and 10'.

40 In Fig. 3 there is shown a second embodiment of the bubble-forming ring in which the ring is formed of a multiplicity of small rigid strands 10b, these strands being loosely twisted together for purposes of rigidity and to provide a multiplicity of small capillary spaces therebetween. If desired, the handle as well as the ring may be formed of said twisted multiple strands. However, in Fig. 3 there is illustrated one embodiment of the wand in which the handle is formed

45

of another material, such as a tube 14 of metal, one end of which has been provided with a channel 15 to accommodate the end 19 of the twisted strands which form the ring 11. It is to be understood that the handle in any of the embodiments of the wand of the present invention may be formed of the multiple strands or may be formed of another rigid material, such as wood, glass, plastics, metal, fibre board, or the like.

It is not necessary that all the elements of the multiple strands which comprise the ring be formed of the same material. As a matter of fact, it is advantageous in some cases to have some of the strand elements formed of rigid, non-fibrous strands, for example, wires of metal, and have the other strands of the ring formed of other fibrous material, e. g. threads. The embodiment is illustrated in cross-section in Fig. 4 in which the bubble-forming ring comprises a multiplicity of strands, some of the strands 10c being formed of metal wires while the other strands 10d are formed of textile threads, preferably threads formed of staple fibres so that the thread has a substantial nap. Accordingly, the nap fibres tend to increase the total surface area exposed to the liquid and thus increase the volume of liquid carried by the multistranded ring.

There is shown in Fig. 5 another embodiment in which the ring comprises a central rigid strand 10e formed, for example, of a heavy metallic iron about which a finer wire 16 is coiled. The finer gauged wire is preferably coiled loosely, thus providing a multiplicity of small capillaries between the central wire 10e and the surrounding coil 16 as well as between the individual turns of the coil. As a result of the capillaries, a ring of the construction shown in Fig. 5 will carry a greater volume of liquid than a ring formed from a single strand having the same surface area as provided by the multiple strands.

In Fig. 5 there is shown also a special embodiment of the handle, it being understood that this embodiment of the handle may be used with

any of the rings shown in any of the other embodiments. Referring to Fig. 5, the handle is formed of a strand bent back upon itself to form an elongated loop 17.

In Fig. 6 there is shown another embodiment of the multistrand wand in which the ring is formed from a single filamentary strand 18 which is wound twice upon itself to form closely conforming rings 19 and 19' having small capillary spaces existing therebetween. The two ends of the wire may project from the rings 19 to form a handle as shown. One or both of the ends may be bent backward to form an elongated loop 17.

While reference has been made to forming the strands of metallic wire, it is to be understood that any other rigid material may be employed, such as stiff filaments of synthetic resins and filaments of glass; also plastic coated threads may be employed as the stiff strands. Moreover, the strands need not be circular in cross-section but may have any cylindrical cross section, either square, triangular, elliptical, or the like.

I claim:

1. A bubble-forming wand comprising a handle, a loop on one end of the handle, said loop comprising a plurality of wires twisted together, adjacent courses of said wires contacting each other only at spaced points leaving capillary spaces therebetween.

2. A bubble-forming wand as recited in claim 1 in which one of said wires is twisted in a helix about the other wire.

AUGUST RASPET.
